(No Model.)

C. BURPEE.
CAR COUPLING.

No. 433,514.

Patented Aug. 5, 1890.

UNITED STATES PATENT OFFICE.

CHARLES BURPEE, OF ROWENA, NEW BRUNSWICK, CANADA, ASSIGNOR TO
GEORGE F. BURPEE, OF WILMOT, AND CHARLES L. TILLEY, OF WAKEFIELD, CANADA.

CAR-COUPING.

SPECIFICATION forming part of Letters Patent No. 433,514, dated August 5, 1890.

Application filed May 28, 1890. Serial No. 353,447. (No model.)

To all whom it may concern:

Be it known that I, CHARLES BURPEE, a citizen of the Dominion of Canada, residing at Rowena, in the county of Victoria and Province of New Brunswick, Canada, have invented a new and useful Car-Coupling, of which the following is a specification.

This invention relates to railway-car couplings, and more especially of that class in which the operation of coupling is automatically performed; and the object of this invention is to improve the construction of existing devices of this general character.

To this end the invention consists of a weight-block pivoted in the draw-head, the object of which is to hold the link in a horizontal position while leaving it free to be moved in any direction necessary, and a lever-catch supported by a pin in the weight-block, which is both a pivot and fulcrum for the said lever-catch, the weight of which supports the coupling-pin which moves in the front end of the said weight-block, together with the other specific details of construction and auxiliaries tending to enhance the value of the whole, all as hereinafter more fully described, and illustrated in the drawings, in which—

Figure 1 is a side elevation of this car-coupler. Fig. 2 is a central longitudinal section showing the link as locked therein. Fig. 3 is a similar section showing the link as removed and the pin ready to fall through an approaching link. Fig. 4 is a similar section showing the pin withdrawn from link and supported by the catch, the link being ready for removal from the draw-head. Fig. 5 is a perspective detail of the weight-block and catch. Fig. 6 is a section on the line 6 6 in Fig. 2.

Referring to the said drawings, the letter H designates the draw-head, P the coupling-pin, and L the link, which are all of the ordinary or any preferred construction. W is a weight-block back of the coupling-pin, pivoted on a transverse pin w, passing through its rear end and through the side of the draw-head each side of the opening therein, and this

weight-block has a staple or ring R for elevating the block when desired. Within the weight-block, on a pin k, is pivoted a lever-catch K, whose front end is arranged in the lower part of a notch N in the front end of the weight-block, the pivot of the catch being so arranged that the catch will normally assume the position shown in Fig. 3—that is to say, with its front end or tip beneath the lower end of the coupling-pin P, whereby said pin is supported by the weight of the catch acting as a lever, the pin k supporting the catch being the fulcrum.

The notch N in the front end of the weight-block registers with a similar notch in the body of the draw-head, and the two notches form a vertical hole through which the pin P moves, as will be understood. The lower forward corners of the weight-block at either side of the catch are beveled, about as shown at V, and the lower end of the catch is also beveled as shown.

In operation, when the parts stand in the position shown in Fig. 3, an approaching link being held in a level position by its weight-block and fulcrum, as shown in Fig. 2, enters the draw-head and, striking the beveled ends of the weight-block and catch, presses the latter rearwardly around its pivot k, and the pin P falls through the link to the position shown in Fig. 2, the beveled ends of the weight-block guiding the link to its place under the weight-block, the weight of which is sufficient to hold the link horizontal over the corner h of the mouth of the draw-head, which is extended slightly forward and forms a fulcrum for this purpose.

It is sometimes desirable, when uncoupling and cars are not ready to move at once and pull the link L from the uncoupled car, to withdraw the pin from the link and return it to its place in the registering notches and leave it there supported by the catch, as shown in Fig. 4. In this case, after removing the pin, the weight-block is slightly raised by the ring or staple R, which permits the catch K to turn on its pivot k, so that its lower end will rest

on the top of the link L, and when the link is withdrawn the block, catch, and pin fall into the same position, as shown in Fig. 3.

What I claim is—

- 5 1. In a car-coupling, the combination, with the draw-head, the weight-block pivoted there-in and having a notch in its front end regis-tering with a notch in the draw-head, and the pin-supporting catch pivotally mounted with-in 10 said weight-block, of a pin seated in said registering notches and normally resting upon said catch, substantially as described.
- 15 2. In a car-coupling, the combination, with the draw-head, the weight-block pivoted there-in and having a notch in its front end regis-tering with a notch in the draw-head, the

lower front corners of said weight-block be-ing beveled, and the pin-supporting catch piv-otally mounted within said weight-block and having its front end also beveled, of a pin 20 seated in said registering notches and nor-mally resting upon the front end of the catch, the whole operating substantially as de-scribed.

In testimony that I claim the foregoing as 25 my own I have hereto affixed my signature in presence of two witnesses.

CHARLES BURPEE.

Witnesses:

CHARLES L. TILLEY,
D. McL. VINCE.
